UNITED STATES PATENT OFFICE.

ALVA D. JONES, OF PHILADELPHIA, PENNSYLVANIA.

DESIGN FOR A CABINET FOR TALKING-MACHINES.

48,976.

Specification for Design.

Patented May 2, 1916.

Application filed February 16, 1916. Serial No. 78,775. Term of patent 3½ years.

To all whom it may concern:

Be it known that I, ALVA D. JONES, a citizen of the United States, and a resident of the city of Philadelphia, county of Philadelphia, State of Pennsylvania (whose post-office address is 601 Witherspoon Building,) have invented a new, original, and ornamental Design for Cabinets for Talking-Machines, of which the following is a specification, reference being had to the accompanying drawing, forming a part hereof.

The figure is a perspective view of a cabinet for a talking machine showing my new design.

I claim:

The ornamental design for a cabinet for a talking machine as shown.

ALVA D. JONES.

Witnesses:

VERNON STANTON,
MILICENT ROGERS.
